AUTOMATIC LOCK FOR SMALL SHAFTS
Howard W. Cole, Jr., 12 Vale Drive,
Mountain Lakes, N.J.
Filed June 8, 1959, Ser. No. 818,680
9 Claims. (Cl. 188—134)

This invention relates to shaft locks of the type where-in a driven connector can be rotated from a driving connector, but rotary force applied to the driven connector cannot be transmitted back to the driving connector.

One successful type of shaft lock employs over-running brakes which have two sets of brake rollers, one set of which jams to prevent rotation of a driven connector in one direction, and the other set of which jams to prevent rotation of the driven connector in the other direction. Such shaft locks are provided with means for releasing the jammed brake rollers when the driving connector is actuated. There are motion-transmitting connections between the driving connector and the driven connector with lost motion so that the driving connector will operate the jammed brake rollers to release them before taking up the lost motion between it and the driven connector.

It is an object of this invention to provide an improved shaft lock, of the character indicated; and more especially, it is an object of this invention to provide a shaft lock in which opposing reactions are set up to release the locking element, and these opposing reaction forces are exerted on the locking element themselves.

In the most efficient shaft locks of the prior art, it has been the practice to employ blocks or shoes for moving the locking elements of the brake into released positions; and it is an object of this invention to provide a simplified construction which makes the unlocking of blocks or shoes unnecessary by exerting the unlocking or releasing forces directly on the locking elements, or rollers, of the brake.

Another object of the invention is to provide an improved automatic shaft lock, of the character indicated, with means for adjusting the back-lash of the locking elements of the brake, and in one embodiment of the invention, such adjustment is provided for each individual locking element.

One of the advantages of the present invention, with its simplified construction, is the suitability of the invention for shaft locks of very small size. The use of fewer parts is especially advantageous in very small shaft locks because the parts have to be accurately made and the cost is substantially reduced by having fewer parts.

Other objects, features and advantages of the invention will appear or be pointed out as the description proceeds.

In the drawing, forming a part hereof, in which like reference characters indicate corresponding parts in all the views;

FIGURE 1 is a sectional view, taken on the line 1—1 of FIGURE 2;

FIGURE 2 is a sectional view through an actuator made in accordance with this invention, the section being taken on the line 2—2 of FIGURE 1;

FIGURES 3 and 4 are sectional views taken on the lines 3—3 and 4—4, respectively, of FIGURE 2; and

FIGURE 5 is a view similar to FIGURE 2, but on a reduced scale and showing a modified form of the invention.

The actuator construction shown in the drawing includes a fixed frame 10 to which is connected a housing 11. An outer brake element 12 is secured to the housing 11 and is a fixed unit with the frame 10 and the housing 11. The outer brake element 12 is shown as a

2

cylindrical sleeve and its inner surface provides a bearing for a driven connector 14 and for rollers 16 which comprise the locking elements of the brake. These rollers 16 contact with the inner surface of the outer brake element 12 beyond a shoulder 17 of the driven connector 14.

The housing 11 has a cylindrical bearing surface 18 beyond the outer brake element 12, and in the construction shown, the bearing surface 18 is flush with the bearing surface in the brake element 12, but this is not essential, nor is it necessary that these bearing surfaces be cylindrical. They may be tapered or may be zone surfaces of a sphere or have other contours about a longitudinal axis, indicated by the line 20 in FIGURE 2 and by the point 20 in FIGURES 1, 3 and 4. The construction illustrated with a continuous cylindrical bearing in the outer brake element 12 and the housing 11 has the advantages of being more economical to manufacture.

A driving connector 22 extends into the housing 11, at the opposite end from the driven connector 14 and this driving connector 22 rotates in the bearing provided by the surface 18. A counter-bore 24 in one end of the driving connector 22 receives a reduced-diameter end of the driven connector 14 and the driving connector 22 is connected with the driven connector 14 by a pin 26 which is rigidly secured to one of the connectors and which passes through an opening in the other connector with clearance to provide lost motion in the connection formed by the pin 26.

In the construction illustrated, the pin 26 fits tightly in the end of the driven connector 14 and passes loosely through an opening 28 in the end portion of the driving connector 22. Thus the pin 26 transmits rotary motion of the driving connector 22 to the driven connector 14 but with some lost motion at the start of the rotation in either direction for releasing the locking elements of the brake, as will be more fully explained.

There is an annular groove 30 in the circumference of the driving connector 22 for holding a sealing ring 32. This sealing ring 32 fits into a counter-bore 34 in one end of the housing 11. There is a retainer 36 around the driving connector 22 and within the counter-bore 34; and this retainer 36 is held in place by a snap ring 38 which fits into a circumferential groove 40 in

the driving connector 22 just beyond the end face of the housing 11. This snap ring 38 extends radially part way across the end face of the housing 11 and provides a thrust bearing for preventing movement of the driving connector 22, and its connected parts, toward the right in FIGURE 2.

A pin 42 extends through the driven connector 14 just beyond the other end of the housing 11 and extends across the end face of the housing 11 to serve as a thrust bearing for preventing the driven connector 14 and its connected parts from being displaced toward the left in FIGURE 2. This pin 42 also serves to limit the rotation of the mechanism, there being a stud 44 extending from the end face of the housing 11 in the path of the pin 42. This limits rotation of the driven connector 14 to something less than 360°.

The apparatus illustrated is intended particularly for operating a potentiometer where less than a full circle of movement is desired; but it will be understood that the invention can be applied to other installations where a number of revolutions, or unlimited numbers of revolutions may be desirable; and in such a case no stop, such as the stud 44, would be provided.

The actuator as shown in the drawing does not show the means by which the driving connector 22 is rotated or the means which are turned by the driven connector 14. It will be understood that the driving connector 22 can be rotated by a tool, a manually-actuated operator, a motor or any other expedient for imparting rotary motion

to the connector 22. It will be further understood that the driven connector 14 can be connected to a potentiometer brush, to a gear, crank arm, or any other expedient for producing the motion for which the actuator is used, and for holding the actuated part in the position to which it is shifted by this motion.

The portion of the driven connector 14 between the shoulder 17 and the end face of the driving connector 22 is of non-circular cross section. This non-circular portion of the driven connector 14 is shown in section on FIGURE 1. At its maximum width, the driven connector 14 has arcuate faces 48 which bear against the cylindrical inner bearing surface of the sleeve 12 and are continuations of the cylindrical surface of the driven connector 14 which rotates in the sleeve or outer brake element 12 as a bearing. However, most of the perimeter of the driven connector 14, at the section shown in FIGURE 1, is cut away to provide cam faces 50 with which the locking elements or rollers 16 contact.

In the simplified construction illustrated in the drawing, there are only four rollers 16, two for preventing rotation of the driven connector 14 in one direction, and two for preventing its rotation in the other direction. These rollers 16 of the different sets are urged apart by springs 52. These springs 52 move the rollers 16 in directions to hold them simultaneously in contact with the cylindrical bearing surface of the outer brake element 12 and the face of the particular cam surface 50 which operates against each roller 16. In the construction illustrated, the cam faces 50 are plane surfaces. They may have other contours depending upon the particular mechanical advantage which the designer wishes to obtain in the operation of the shaft lock, but different mechanical advantages can be obtained by changing the angle of these plane surfaces; and there is a distinct advantage in the economy of manufacture by employing plane surfaces for use as the cam faces 50.

Whenever the driven connector 14 tends to turn in a clockwise direction in FIGURE 1, the cam face 50 under the upper left-hand roller 16 will jam that roller against the outer brake element 12 which is fixed, and this prevents rotation of the driven connector 14 in a clockwise direction. The diametrically opposite roller 16, that is, the lower right-hand roller in FIGURE 1, will be similarly jammed against the fixed outer brake element 12. Any time that the driven connector 14 tends to rotate in a counter-clockwise direction, the cam face 50 under the right-hand roller 16 in FIGURE 1, and the corresponding cam face 50 in contact with the lower left-hand roller 16, jam these rollers against the fixed outer brake element 12 and prevent rotation of the driven connector 14 in a counter-clockwise direction.

When the driven connector 14 tends to move counter-clockwise, the movement of the cam faces 50 with respect to the upper left-hand roller 16 and the lower right-hand roller 16 in FIGURE 1 merely tends to open up a clearance for these rollers 16 between the cam faces 50 and the bearing surface of the outer brake element 12. Because the parts are so constructed that the maximum spacing of the cam faces 50 from the cylindrical bearing surface of the outer brake element 12 is slightly greater than the diameters of the rollers 16, the springs 52 push the rollers 16 along the cam faces 50 to locations slightly beyond the region of maximum radial spacing of the cam faces 50 from this inner bearing surface of the outer brake element 12.

Although the locking elements or rollers 16 jam to prevent movement of the driven connector 14 whenever that connector starts to rotate in either direction, they do not prevent rotation of the driving connector 22, nor do they prevent the driven connector 14 from being rotated by force supplied by the driving connector 22 through the pin 26 to the driven connector 14. This result follows from the fact that whichever set of rollers 16 is jammed to prevent rotation of the driven connector 14 in one direction or the other, this set of rollers 16 is released by rotation

of the driving connector 22 with respect to the driven connector 14 and such relative movement is made possible by the lost motion in the connection provided by the pin 26.

Referring to FIGURE 2, the left-hand ends of the rollers 16 extend into recesses 56 in the end face of the driving connector 22. The walls of these recesses 56 provide abutment surfaces which contact with the rollers 16 to move them in a manner which will be more fully described.

The right-hand ends of the rollers 16 extend into recesses 58 in the shoulder 16 of the driven connector 14. In the construction illustrated, the recesses 56 are tapered, but the recesses 58 are cylindrical. When the actuator is properly adjusted, each end of each of the rollers 16 fits loosely in the corresponding socket or recess 56 or 58. The ends of the rollers are thus free to move in the socket 56 and 58. They may rotate or move to a limited extent axially or move into skewed positions, and this combination of movements will be described herein as "universal movement" with respect to the abutment surfaces provided by the walls of the sockets 56 and 58.

The movement of the rollers 16 with respect to the abutment surfaces provided by the sockets 56 and 58, particularly the skewing movement, is necessary in order to obtain the reaction-unlocking feature of this invention. This reaction-unlocking feature makes the actuator operate with the application of less force to the driving connector 22, and it will be best understood by description of the specific operation of the actuator.

For example, the actuator may be considered as locked by the upper right-hand and lower left-hand rollers 16 in FIGURE 1. This means that the actuator has locked in response to an effort by the driven connector 14 to move counter-clockwise. This effort may be the result of a continuous load on the driven connector 14 which tends to rotate that connector in a counter-clockwise direction in FIGURE 1.

The driving connector may be next rotated in a counter-clockwise direction in FIGURE 1; the driving connector 22 being ahead of the plane of section of FIGURE 1, but it being understood that the forward ends of the rollers 16, that is, the end toward the reader in FIGURE 1, are the ones which extend into the recesses 56 (FIGURE 2) of the driving connector 22. Such rotation of the driving connector 22 will take up the small amount of lost motion resulting from the loose fit of the roller 16 in the sockets of the driving connector and will then urge the driving connector ends of the roller 16 to move counter-clockwise in FIGURE 1.

This force urging the driving connector ends of the rollers 16 to move can have two different results. If each of the jammed rollers is not too tightly jammed between the cam face 50 and the inside bearing surface of the fixed brake element 12, the portion of the roller in contact with the cam face 50 will be moved along the cam face toward the left in FIGURE 1 and this will release the jamming of the roller because it will have moved the roller into a position where the distance between the cam face and the fixed outer brake element 12 is of greater radial extent.

If the roller 16 is so tightly jammed between the cam face 50 and the outer brake element 12 that it offers a strong resistance to movement by the driving connector, then the roller 16 will skew about its lines of contact with the cam surface 50 and the outer brake element 12 and this skewing movement will force the driven connector 14 to move clockwise in FIGURE 1. Such movement of the driven connector 14 turns the cam faces 50, and turns them in a direction to release the pressure of the cam faces 50 against the jammed rollers 16 in FIGURE 1, thus releasing the actuator.

From the above description, it will be apparent that a force supplied to locked or jammed rollers 16, by the driving connector 22, sets up a reaction tending to move the

mid portion of each roller 16 in one direction and the driven connector end portion of the roller in the opposite direction. Thus, the actuator is released by either moving the mid portion of the roller 16 along its cam face 50 in a direction to release the actuator or moving the driven connector 14 in a direction to give the cam face 50 a motion that releases the actuator.

Operation of the actuator by the driving connector 22 in a direction in which the actuator is not locked by the upper right-hand and lower left-hand rollers 16 in FIGURE 1 will skew the rollers slightly until the lost motion of the pin 26 (FIGURE 4) is taken up, and then the driving connector 22 will rotate the driven connector 14 in a clockwise direction so as to move the cam surface 50 (FIGURE 1) in the direction which increases the radial clearance between the cam surface and the outer brake element 12 at the location of the upper right-hand and lower left-hand rollers 16 by which the actuator was locked.

Operation of the actuator is dependent upon the proper adjustment of clearance and back-lash of the rollers 16 with respect to the sockets 56 and 58 into which the ends of the rollers extend. It will be evident that the rollers 16 must have sufficient play for lost motion in the sockets so that they can move into skewed positions. It will also be evident that the rollers 16 must have sufficient play so that the rollers by which the actuator is locked, for example, the upper right-hand and the lower left-hand roller 16 in FIGURE 1, so that the motion necessary to release these rollers can take place before the actuator will be locked by the other rollers which resist rotation of the driven connector 14 in the opposite direction. That is, the driven connector 14 must be able to move sufficiently to relieve the pressure of the cam faces 50 against the upper right-hand and lower left-hand roller 16 in FIGURE 1 before the upper right-hand and lower left-hand rollers lock the driven connector 14. In actual practice, this motion is extremely small and in accurately made actuators it is not a noticeable motion of the driven connector 14 but merely a relieving of the stress in one direction without actually producing rotation of the connector 14. Theoretically, this is a motion of the connector, at least to the extent required internally to change the elastic forces exerted by the material of which the driven connector is made.

If the play or clearance between the roller 16 and the recesses 56 and 58 is too small, then the actuator will never unlock in response to rotation of the driving connector 22, because the roller 16 cannot move sufficiently to produce the unlocking action above described. On the other hand, if the clearance of the roller 16 is excessive in the recesses 56 and 58, the actuator will not unlock because the lost motion of the pin 26 will be taken up before the rollers 16 have made the necessary motions to unlock the actuator; and if this occurs the driving connector 22 will be exerting a rotary force to turn the driven connector 14 in such a way as to cause the actuator to lock against rotation in either direction in the same way as if the rotary force were applied directly to the driven connector 14.

The only reason that the actuator can be turned by the driving connector 22, and cannot be turned by rotary force applied directly to the driven connector 14, is that the driving connector 22, when the parts are properly adjusted, unlocks the actuator before the play or lost motion of the pin 26 is taken up and thus before rotation is imparted by the driving connector 22 to the driven connector 14 in the same direction as the driving connector is turning.

In the actuator shown in FIGURES 1-4, the play or back-lash for the rollers 16 is adjusted separately for each individual roller. The structure by which this adjustment is effected is best shown in FIGURE 2. A rod 64 slides freely through an opening 66 in line with each of the recesses 58. At the end of the opening 66 remote

from the recess 58, there is a threaded counterbore 70 which receives a screw 72. This screw 72 is rotated one way or the other to adjust the back-lash of the actuator.

The screw 72 can be used to push the rod 64 to the left in FIGURE 2 to reduce the clearance of the roller 16 in the recess 56. This limits any sliding movement in the recess 58 as well as in the recess 56. Skewing of the roller 16 holds the rod 64 back against the screw 72 and it is not necessary to have any connection between the screw 72 and the rod 64 for pulling the rod 64 toward the right in FIGURE 4 when it is desired to increase the amount of back-lash. It will be understood that all of the rollers 16 have similar adjusting means to that shown for the upper roller 16 in FIGURE 2.

FIGURE 5 shows a modified form of the invention. Corresponding parts in FIGURE 5 are indicated by the same reference characters as in FIGURES 1-4 with a prime appended. The only important difference between the construction shown in FIGURE 5 and that shown in the other figures is in the adjustment of the back-lash of the actuator. Instead of having means for adjusting the clearance and back-lash of each roller individually, the construction shown in FIGURE 5 has means for adjusting the clearance and back-lash for all of the rollers simultaneously. This result is obtained by having the rollers 16' constructed with tapered end portions at both ends of each roller and by having tapered recesses 56' and 58' in the driving connector 22' and the driven connector 14'.

Means are provided for moving the entire driven connector 14' axially with respect to the driving connector 22', to reduce the axial distance between the recesses 56' and 58'. These means include a screw 82 which contacts with a shoulder 84 in a counter-bore at one end of a passage 86 through which the screw 82 extends to a threaded opening 88 in the driving connector 22'. The diameter of the passage 86 is large enough to permit the screw 82 to rotate freely with respect to the driven connector 14', and when the screw 82 is made with the threaded portion long enough to reach into the passage 86, the threads have no effect on the driven connector 14' because there are no threads in the passage 86.

Rotation of the screw 82 in one direction moves the driven connector 14' toward the driving connector 22', as previously explained; and rotation of the screw 82 in the other direction permits the rollers 16', upon their next skewing operation, to push the shoulder of the counter-bore to the right against the head of the screw 82 so that in the operation of the actuator the shoulder at the end of the counter-bore 84 is always in contact with the head of the screw 82.

Because of the axial movement of the driven connector 14' with respect to the driving connector 22', in the adjustment of the back-lash of the actuator shown in FIGURE 5, it is advantageous to have the pin 26' pass through an opening, corresponding to the opening of FIGURE 4, with the opening slightly elongated so that the lost motion of the actuator between the driving connector 22' and the driven connector 14' is not affected by the adjustment of the back-lash. Such elongation provides for greater manufacturing tolerance; but if the actuator is made with precision accuracy, the elongation is not necessary because the amount of lost motion between the driving connector 22' and the driven connector 14' can be less when the actuator is adjusted for reduced back-lash.

The preferred embodiments of the invention have been illustrated and described, but changes and modifications can be made, and some features can be used in different combinations without departing from the invention as defined in the claims.

What is claimed is:

1. An actuator comprising brake means with inner and outer elements, and rollers between the inner and

outer elements, one of said elements having a circular bearing surface with which the rollers contact, and the other of said elements having cam surfaces spaced from the circular bearing surface and that jam some of the rollers against the circular bearing surface when the elements are moved angularly with respect to one another about the center axis of the circular bearing surface, the rollers being angularly spaced from one another about said axis, means for preventing rotation of one of said elements, a driving connector at one end of the rollers, a driven connector at the other end of the rollers, each of the connectors being rotatable about a longitudinal axis substantially coincident with the axis of the circular bearing surface, abutment surfaces on both of the connectors and adjacent to end portions of the rollers and extending into the spaces between successive rollers so that movement of the abutment surfaces about said axis causes movement of the rollers, the end portions of the rollers having universal movement with respect to the abutment surfaces whereby the rollers can skew into positions at different angles with respect to the center axis of the circular bearing surface when moved at either end by the abutment surfaces, and a driving connection between the driving connector and the driven connector, said driving connection having lost motion therein sufficient to cause the driving connector to move the rollers before the lost motion is taken up.

2. The actuator described in claim 1 and in which the circular bearing surface is cylindrical and the rollers contact with said bearing surface for only a portion of the axial length of said bearing surface, but the rollers have limited axial movement that changes their region of contact with the cylindrical surface.

3. The actuator described in claim 1 and in which the driving connector and the driven connector each have a face confronting a corresponding face of the other and extending across the ends of the space between the cam surfaces and the circular bearing surface, and the rollers are located between the confronting faces of the driving connector and the driven connector.

4. The actuator described in claim 3 and in which there are recesses in said confronting faces and the rollers have end portions which extend into the recesses, the sides of said recesses constituting the abutment surfaces that are adjacent to the end portions of the rollers.

5. The actuator described in claim 4 and in which there are opposing faces on an end portion of each roller and the recess of one of the connectors into which the end portion of the roller extends, and in which at least one of said opposing faces is tapered, and there are means adjustable toward and from the recesses in the connector to adjust back-lash of the actuator.

6. The actuator described in claim 5 and in which there are separate means for adjusting each of the rollers to adjust the back-lash of the actuator.

7. The actuator described in claim 5 and in which there are common means for adjusting all of the rollers simultaneously to adjust the back-lash of the actuator.

8. The actuator described in claim 5 and in which all of the rollers have tapered end portions and all of the recesses in both of the connectors are tapered for receiving the tapered end portions of the rollers.

9. An actuator comprising brake means with inner and outer brake elements, rollers between the inner and outer brake elements, the outer brake element having a cylindrical surface with which the rollers contact, means for holding the outer element in a fixed position, cam surfaces on the inner brake element and with which the rollers contact, there being a different cam surface for each roller and the alternating cam surfaces around the brake means being disposed to thrust their rollers outwardly when the inner brake element is rotated in a different direction as the inner brake element rotates about a longitudinal axis, a driving connector having a face at one end of the rollers, and a driven connector by which the cam surfaces are carried, the driven connector having a shoulder with a face at the other end of the rollers, both of the connectors being rotatable about a longitudinal axis, and both of the connectors having confronting faces with sockets into which end portions of the rollers extend with some clearance between the end portion of the rollers and the confronting surfaces of the sockets, whereby the rollers have some lost motion in the sockets and are capable of moving into a skewed position when one of the confronting end faces rotates with respect to the other about said longitudinal axis, and a driving connection between the driving connector and the driven connector, said driving connection having somewhat more lost motion than that of the rollers in the sockets of the confronting end faces.
